US00D534514S

(12) **United States Design Patent** (10) **Patent No.:** **US D534,514 S**
Hering (45) **Date of Patent:** **** Jan. 2, 2007**

(54) **COMMUNICATOR**

(75) Inventor: **Jean-Marc Hering**, Salo (FI)
(73) Assignee: **Nokia Corporation**, Espoo (FI)
(**) Term: **14 Years**
(21) Appl. No.: **29/224,328**
(22) Filed: **Mar. 1, 2005**

(30) **Foreign Application Priority Data**

Sep. 2, 2004 (FI) M20040137
(51) **LOC (8) CI** **14-03**
(52) **U.S. Cl.** **D14/138**; D14/345
(58) **Field of Classification Search** D14/137,
D14/138, 147-148, 247-248, 144, 218, 341-347,
D14/455, 456; 379/433.01-433.13, 434;
455/575.1, 566, 556.1; D21/517, 329, 331;
345/169

See application file for complete search history.
